KNOCKDOWN FRUIT BOX

John Spanjer, Ephrata, Wash.

Application January 26, 1949, Serial No. 72,791

2 Claims. (Cl. 217—12)

1

This invention relates to a container, and more particularly to a container which can be collapsed as desired.

The object of the invention is to provide a container for shipping merchandise therein, such as fruit, and which can be collapsed after the merchandise has been removed in order to occupy a minimum of space.

Another object of the invention is to provide a receptacle which can be readily assembled to provide a rugged and safe shipping case for freight, and which, when empty, can be quickly disassembled whereby a plurality of the disassembled boxes can be returned to the growers in a minimum of space so that the freight charges for returning the empty cases will not be excessive.

A further object of the invention is to provide a collapsible container which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a side elevational view of the shipping case according to the present invention;

Figure 2 is an elevational view of one end of the case;

Figure 3 is an elevational view of the other end of the case;

Figure 4 is a sectional view taken on the line 4—4 of Figure 2;

Figure 5 is a sectional view taken on the line 5—5 of Figure 1;

Figure 6 is a sectional view taken on the line 6—6 of Figure 1;

Figure 7 is a perspective view illustrating certain constructional details of the one corner of the case;

Figure 8 is a perspective view illustrating certain constructional details of another corner of the case;

Figure 9 is a side elevational view of the rod for connecting the hinge sections together.

Referring in detail to the drawings, the box or shipping case is adapted to be collapsed or disassembled when not in use, and the case comprises a first rectangular end member 20 fabricated of plastic or fiberboard and provided with four metal L-beams or angle irons 21. The angle irons 21 are arranged contiguous to and parallel with the edges of the end member 20 and each angle iron 21 has a leg 22 secured to the

2

end member 20 by securing elements, such as rivets 23. A second rectangular end member 24 is arranged in spaced, parallel relation with respect to the end member 20, and the end member 24 has a pair of spaced, parallel angle irons 25 secured thereto by rivets 23. The angle irons 25 are arranged contiguous to and parallel with the top and bottom edges of the end member 24.

A top wall 27 and a bottom wall 28 are arranged in spaced, parallel relation with respect to each other and these walls extend between the end members 20 and 24. The top and bottom walls have the same construction and are therefore interchangeable. Thus, a pair of angle irons 29 are spaced from the ends of the walls 27 and 28 and the angle irons 29 abut the end members 20 and 24 when the case or box is assembled. Each of the top and bottom walls has secured to each of its ends by rivets a transversely-extending hook member 30 which slidably receives and holds therein the corresponding angle iron that is secured to the end members.

Arranged at right angles with respect to the top and bottom walls of the case or crate is a pair of spaced, parallel side members 31 which each has the same construction and each includes a pair of spaced, parallel boards or slats 33 and 34. Each side member 31 has a transversely-arranged, elongated hook member 35 secured thereto for engagement with the pair of vertically-disposed angle irons 21 on the end member 20. The other end of each of the side members 33 and 34 has secured thereto a hinge section 36 which is adapted to be connected to a corresponding hinge section 37 by a rod 38 provided with a transverse hook 39 on one end thereof. There are a pair of these hinge sections 37 secured to the sides of the end member 24.

The end members 20 and 24 are each provided with a plurality of locks or catches 40 which are pivotally connected thereto by pins 41. These locks are mounted for movement into and out of registry or engagement with notches 42 which are arranged in the angle irons 29 that are secured to the top and bottom walls, whereby shifting movement of the top wall and side walls will be prevented.

In assembling the case, the end member is held in a vertical position, and the hook members 30 on one end of the top wall 27 and bottom wall 28 are moved or slid into engagement with the horizontally-disposed angle irons 21 on the end member 20. Then, the hook members 35 of the side members 31 are moved into engagement with the vertically-disposed angle irons 21

on the end member 20. Then, the other end member 24 is arranged so that its pairs of angle irons 25 engage with or are held by the hook members 30 on the other ends of the top and bottom walls. Finally, the hinge sections 36 on the side members 31 are aligned with the hinge sections 37 on the end member 24, and the rod 38 inserted therethrough to hold the box in assembled relation.

Fruit or other merchandise can be safely shipped in the box, and after the case or box is emptied, the case can be readily disassembled and a large number of the boxes packed in a small space to reduce the cost of freight in returning the cases.

As many embodiments may be made of this inventive concept, and as many modifications may be made in the embodiment hereinbefore shown and described, it is to be understood that all matter herein is to be interpreted merely as 20 illustrative and not in a limiting sense.

I claim:

1. A collapsible case comprising a first rectangular end member, an angle iron arranged contiguous to and parallel with each of the edges of said end member and secured to the latter, a second rectangular end member arranged in spaced, parallel relation with respect to said first end member, an angle iron arranged contiguous to and parallel with the upper and lower edges of said second end member and secured thereto, a hinge section arranged contiguous to and parallel with each side edge of said second end member and secured thereto, a top wall and a bottom wall arranged in spaced, parallel relation with respect to each other and extending between said end members, a transversely-extending angle iron spaced from each end of said top and bottom walls and abutting said end members, a transversely-extending elongated hook member secured to each end of said top and bottom walls for slidably receiving and holding therein the complemental angle irons on said end members, a pair of spaced, parallel side members arranged at right angles with respect to said top and bottom walls and extending between said end members, a horizontally-extending elongated hook member secured to an end of each of the side members

5

for slidably receiving and holding therein the angle irons arranged along the side edges of said first end member, a hinge section secured to the other end of each of said side members, and 5 means detachably connecting the hinge section on said second end member to the hinge section of said side member.

2. A collapsible case comprising a first rectangular end member, an angle iron arranged contiguous to each of the edges of said end member and secured to the latter, a second rectangular end member arranged in spaced parallel relation with respect to said first end member, an angle iron arranged contiguous to the 15 upper and lower edges of said second end member and secured thereto, a hinge section arranged contiguous to each side edge of said second end member and secured thereto, a top wall and a bottom wall arranged in spaced parallel relation with respect to each other and extending between said end members, a transversely-extending angle iron spaced from each end of said top and bottom walls and abutting said end members, a transversely-extending elongated hook member secured to each end of said top and bottom walls for slidably receiving and holding therein the complemental angle irons on said end members, a pair of spaced parallel side members extending between said end members, a horizontally-extending elongated hook member secured to an end of each of the side members for slidably receiving and holding therein the angle irons arranged along the side edges of said first end member, a hinge section secured to the other end of each of said side members, and means detachably connecting the hinge section on said second end member to the hinge section of said side member.

45

2. A collapsible case comprising a first rectangular end member, an angle iron arranged contiguous to each of the edges of said end member and secured to the latter, a second rectangular end member arranged in spaced parallel relation with respect to said first end member, an angle iron arranged contiguous to the 15 upper and lower edges of said second end member and secured thereto, a hinge section arranged contiguous to each side edge of said second end member and secured thereto, a top wall and a bottom wall arranged in spaced parallel relation with respect to each other and extending between said end members, a transversely-extending angle iron spaced from each end of said top and bottom walls and abutting said end members, a transversely-extending elongated hook member secured to each end of said top and bottom walls for slidably receiving and holding therein the complemental angle irons on said end members, a pair of spaced parallel side members extending between said end members, a horizontally-extending elongated hook member secured to an end of each of the side members for slidably receiving and holding therein the angle irons arranged along the side edges of said first end member, a hinge section secured to the other end of each of said side members, and means detachably connecting the hinge section on said second end member to the hinge section of said side member.
